UNITED STATES PATENT OFFICE

ERNEST M. WHITNEY, OF PROVIDENCE, RHODE ISLAND, ASSIGNOR TO HOOKLESS FASTENER COMPANY, A CORPORATION OF PENNSYLVANIA

LOCK SLIDER FOR SLIDE FASTENERS

Application filed May 14, 1930. Serial No. 452,351.

This invention relates to slide fasteners of the same general construction as shown in the patent to Sundback No. 1,219,881, March 20, 1917, and particularly to improved means for preventing unintended opening of the fastener.

So-called lock sliders of various types have been heretofore devised and used in commercial quantities in conjunction with slide fasteners on various articles. The purpose of the locking feature of these lock sliders is to prevent slipping of the slider back along the fastener after it has been moved to the desired position. A slider without some such locking device may be moved along the fastener elements when lateral strain is placed on the fastener stringers in the locality of the slider, and thus permit the fastener to open up in service.

The present invention has for one of its objects the provision of an improved lock slider of simplified construction and one which is particularly adapted to rivetless sliders, that is, sliders whose wings are not held together by a rivet passing through the wings. The present invention is, however, not necessarily limited to rivetless sliders.

Another object is to provide an improved construction of a slider which has a rigid neck, in which there is incorporated a locking device operated by a cam member on the pull similar to the device shown in my former Patent No. 1,508,183, August 31, 1926.

In the preferred mode of carrying out my invention, a slider with a rigid portion or lug extending adjacent the top wing has at least a portion of the wing movable relative to the lug. An operating member which can be attached to the lug has a cam device for engaging and forcing the movable portion toward the lower wing of the slider, thus clamping the slider against relative movement by frictional engagement with the fastener elements.

Other objects and advantages of my invention will more fully appear during the course of the following specification, and the novel features of construction will be particularly pointed out in the appended claims.

In the accompanying drawings, I have

shown for purposes of illustration, one embodiment which my invention may assume in practice. In these drawings:

Fig. 1 is a plan view of a slide fastener having my invention incorporated therewith.

Fig. 2 is a perspective view of the slider of my invention with the pull member removed.

Fig. 3 is a central longitudinal sectional view through the slider.

Fig. 4 is a longitudinal sectional view through the fastener showing the slider in locked position.

Fig. 5 is a perspective view of the pull member.

Fig. 6 is a sectional view similar to Fig. 4 showing the pull member raised and the slider unlocked.

Fig. 7 is a cross-sectional view through the slider and pull attaching lug.

The slide fastener with which my invention is used may be of any of the known types, the one illustrated having a pair of fabric stringers 8 and 9 with interlocking fastener elements 10 and 11 secured to the adjacent longitudinal edges of the fabric stringers.

These fastener elements are brought together and progressively interlocked or disengaged by movement of a slider generally designated 12, in a manner which is well understood in the art, and described in detail in the above mentioned patent to Sundback No. 1,219,881.

In the embodiment, the general construction of the slider is similar to that shown and described in the Sundback Patent No. 1,661,144, although, of course, the present invention is not at all limited to use in the specific type of fastener illustrated in that patent, but may be applied equally as well to other known sliders.

The slider shown comprises overlying spaced upper and lower wings 13 and 14 respectively, having inturned edges providing flanges 15 which engage the ends of the fastener elements and define a substantially Y-shaped channel through which the stringers pass during interlocking. The wings 13 and 14 are joined together at the rear end of the slider by a rigid neck 16 which, in the present instance, is formed of deformed

wing material preferably by a coining process, although the same may be deformed by indenting the sheet metal of the slider. Such a slider can be formed from a blank which has 5 an integral thickened portion coined up from the metal of the slider blank, such portion being bent between the wings so that the metal on the inner side of the bend is materially compacted and strengthened, thus providing a very compact and rigid neck connection for the wings. The metal of this thickened portion preferably extends longitudinally part way of the wings to form the integral reinforces 17 and 18 on the upper and 10 lower wings respectively. The rigid portion or lug 19 extends adjacent the wing and is preferably joined to the wing connecting portion or neck 16. It can also be formed integrally with the wing material by a coining 15 or similar operation. In the present instance, the lug extends over the greater part of the length of the slider and serves as an attaching lug for the pull member 20. This pull member is a generally flat metal plate 20 having inwardly extending pivotal bearings 21 engaging in the indentations or recesses 25 of the attaching lug 19.

It will now be noted that the front portion 30 of the pull attaching lug 19 is cut away from the metal of the top wing for the greater part of its length by slitting the wing material as indicated at 23. Since the wing material between the ends of the slit 23 and the rear end of the slider is relatively thin, the top 35 wing can be readily flexed into engagement with the fastener elements which are thus securely clamped between the two wings as shown in Fig. 4. The desired clamping action may be readily obtained by providing a pair 40 of cam projections or lugs 24 on the under side of the pull adjacent the pivot bearings 21. When it is desired to lock the slider stationary, the pull member is moved to the forward end of its travel relative to the slider 45 and depressed against the fastener. The rounded cam projections 24 will bear against the wing 13 and press it downwardly, thus clamping the fastener elements 10 and 11 and locking the slider effectively by friction. 50 It will be apparent that during the locking or clamping action the slider will be subjected to a spreading strain, but the lug 19 joined by the reinforce 17, neck 16, and reinforce 18 to the lower wing, provides a very strong 55 connection for resisting the clamping stresses. If the parts are made accurately, there will never need to be any undue strain placed upon the reinforcing neck in order to provide sufficient friction between the slider wings and fastener elements to prevent 60 movement of the slider under all ordinary circumstances of use. When the fastener is being closed under strain, the tendency of the wings to spread apart is effectively resisted since the lug 19 is rigidly joined to

the lower wing and the upper wing is prevented from upward movement by engagement with the pull member.

As a result of my invention, it will be observed that all of the advantages of a lock slider operating on the friction principle are utilized in a rivetless slider with a very slight addition to the cost of manufacture. The only changes from standard manufacturing processes used in making non-locking sliders of the type illustrated would be the formation of the slit 23 and the cam lugs or projections 24 on the pull member.

While I have in this application specifically described one embodiment which my invention may assume in practice, it will be understood that this embodiment is merely for the purposes of illustration and description and that various other forms may be devised within the scope of my invention as defined in the appended claims.

What I claim as my invention is:

1. In a slide fastener, cooperating fastener elements for separably connecting adjacent edges of an article to be fastened, a slider movable along said elements for engaging and releasing the same, said slider comprising overlying spaced wings, an integral neck connection for said wings, a lug integrally joined to said connection and extending adjacent the top wing, a portion of said top wing being movable relative to said lug, and a cam member attached to said lug adapted in one position to clamp the wings of the slider upon said fastener elements.

2. In a slide fastener, cooperating fastener elements for separably connecting adjacent edges of an article to be fastened, a slider movable along said elements for engaging and releasing the elements, said slider comprising overlying top and bottom wings, an integral reinforcing connection of deformed wing material between said wings, an integral projection joined to said reinforcing connection and extending over said top wing, a portion of said top wing being cut away from said lug so as to be movable relative thereto, and a slider actuating member attached to said lug having a cam projection adapted in one position of the pull member to depress said movable portion of the top wing into locking engagement with said fastener elements.

3. In a slide fastener, cooperating fastener elements for separably connecting adjacent edges of an article to be fastened, a slider movable along said elements for engaging and releasing the same, said slider comprising spaced top and bottom wings, a neck directly connecting said wings, integral longitudinal reinforces extending from said neck, said neck and reinforces being shaped to maintain the wings in spaced relation independently of any other wing-holding means, a lug joined to one of said reinforces and

extending over the top wing, a portion of said top wing being flexible relative to said neck and lug, and a slider pull member mounted on said lug and having a cam projection for engaging said flexible wing portion to force the same into locking engagement with the fastener elements.

4. A slider for slide fasteners comprising overlying wings having means for guiding 10 interlocking members, integral connecting and reinforcing means bent between said wings, an attaching lug rigidly joined to said wing connecting means and extending over one of said wings, the free end of such 15 wing being cut away from the lug and flexible relative thereto, and a cam member attached to said lug for depressing the flexible end of such wing to lock the slider.

5. A slider for slide fasteners comprising 20 overlying wings having means for guiding interlocking members, said slider having means joining said wings and a rigid extension integral with said joining means adjacent one wing, a part at least of said last 25 mentioned wing being flexible relative to said rigid extension to act as a slider lock, a pull member pivoted to said rigid extension and having a cam adapted to act on said flexible portion to lock the slider.

6. A slider for slide fasteners comprising overlying wings having means for guiding 30 interlocking members, a connection between said wings, one of said wings being slotted to provide a relatively flexible portion, and a 35 cam member attached to the slider for flexing said portion to lock the slider.

7. In a slide fastener, cooperating fastener elements for separably connecting adjacent 40 edges of an article to be fastened, a slider movable along said elements for engaging and releasing the same, said slider comprising overlying spaced wings, a rigid neck connection for said wings, a lug integral with and extending longitudinally from said neck 45 connection, a portion of the top wing being movable relative to said lug, and a cam member attached to said lug adapted in one position to clamp the slider upon said fastener elements.

8. A slider for slide fasteners comprising 50 a pair of spaced-apart substantially parallel wings, a rigid neck for joining said wings at one end, one of said wings being rigidly attached to said neck and the other of said 55 wings having at least a portion flexibly attached to said neck, said neck having a longitudinal extension constituting a pull attaching lug, a pull member connected to said lug, and a cam on said pull member engageable with said flexible wing portion to press the same toward said rigidly connected wing for locking the slider.

In testimony whereof I affix my signature.
